UNITED STATES PATENT OFFICE.

HARVEY HUESTIS, OF PROVIDENCE, RHODE ISLAND.

DESIGN FOR A RING-SETTING.

SPECIFICATION forming part of Design No. 16,126, dated June 16, 1885.

Application filed February 10, 1885. Term of patent 7 years.

To all whom it may concern:

Be it known that I, HARVEY HUESTIS, of the city and county of Providence, and State of Rhode Island, have invented a new and original Design for Settings for Rings, of which the following is a full, clear, and exact description, reference being had to the accompanying drawings, forming a part of this specification.

10 The leading feature of my design consists in a ring-setting having plain surfaces alternating with fluted, ribbed, or corrugated surfaces, and surrounding the stone or jewel mounted in the setting.

15 In the drawings, Figure 1 is a plan view of a square setting having curved angles. Fig. 2 is a similar view of a square setting having plain angles. Fig. 3 is a similar view of an oval setting. Fig. 4 is a side elevation of the 20 design shown in Fig. 3.

In the said drawings, A designates the hoop, band, or loop of the ring, and B designates the jewel. The band may be ornamented with the raised and fluted, ribbed, or corrugated sections a, if desired. The setting is shown with plain surfaces c, alternating with fluted, ribbed,

or corrugated surfaces d, said surfaces embracing the top and outer side of the setting.

As shown in Fig. 1, the setting is square, with its angles curved, in Fig. 2 the setting is 30 square with plain angles, and in Fig. 3 the setting is oval. By this disposition of the plain and fluted, ribbed, or corrugated surfaces a highly ornamental appearance is produced.

35 The design is applicable to fancy or plain forms of settings generally.

Having thus described my new and original design, I claim as new and desire to secure by Letters Patent—

1. The design for a ring-setting, consisting of the alternated corrugated and plain surfaces on the outer sides and upper edges of the setting-rim, as shown.

2. The design for ring-settings, consisting 45 of the plain sections c, the corrugated sections d, and the side sections, a a, corrugated on their upper surfaces, as shown.

HARVEY HUESTIS.
